SOLDERLESS CONNECTER

Ernest G. Johansson, Watertown, Mass., assignor
to The Palmer Electric & Manufacturing Co.,
Waltham, Mass., a corporation of Massachu-
sets

Application April 4, 1935, Serial No. 14,612

3 Claims. (Cl. 173—263)

This invention relates to solderless connectors for electrical conductors. Electrical connections, especially where heavy currents are to be carried, are usually soldered where possible, so as to provide a good interfacial contact between the conductors which are connected. There are occasions, however, where soldering may not be available or possible. In such cases solderless connectors must be employed. When using such connectors, it is important that the contacting faces be of maximum area and that they be firmly pressed together to minimize electrical resistance at the point of contact and the heating effect which results from local resistance.

According to the present invention, a simple but effective solderless connector is provided, this connector being of small size relative to its current-carrying capacity, being inexpensive to manufacture, requiring the use of no tool except an ordinary screw driver, and being adapted to receive conductors of various diameters up to a certain limit.

For a more complete understanding of the invention, reference may be had to the description of an embodiment thereof which follows, and to the illustration thereof on the drawing of which—

Figure 1 is a plan view of one of the members of the improved connector in the course of manufacture.

Figure 2 is an elevation of the same member after it has been bent to shape.

Figure 3 is a plan view of a sheet metal blank for another member of the connector.

Figure 4 is a plan view of the same after it has been bent to shape.

Figure 5 is an elevation of the members of a connector and a portion of a conductor to be secured therein.

Figure 6 is a plan view of a connector assembled with a conductor.

Figure 7 is a section on the line 7—7 of Figure 6.

Figure 8 is a section on the line 8—8 of Figure 6.

Figure 9 is a sectional view of the connector showing it assembled with two conductors.

Figure 10 shows in plan view a connector mounted as a terminal and connected to a conductor.

Figure 11 is an elevation of the structure shown in Figure 10.

Figure 12 is a sectional view of a screw which may be employed as a member of the connector.

Referring to the drawing in detail, Figure 1 represents a piece of strip metal stock 10 which

is cut to suitable length to be bent into U-shaped form as shown in Figure 2. Prior to the bending of the strip 10, a hole 11 may be punched, drilled, or otherwise formed in the center of the strip, and a pair of groove segments 12 and 13 may be swaged or gouged in a face of the strip 10, these groove segments being preferably aligned with each other and extending along the longitudinal median of the strip. The strip 10 is then bent on the lines a—a and b—b into U-form so that the hole 11 is in the bottom of the U, and grooves 12 and 13 are on the inside opposed faces of the legs 15 and 16 of the U. The legs are then held by any suitable means against spreading while the grooves 12 and 13 are tapped with a thread-cutting tool to form a screw thread therein.

As shown in Figure 3, a second member 20 may be cut from metal sheet stock to form an H-shape comprising a pair of side members 21 and 22 connected by a crosshead 23. The side members 21 and 22 are slit as at 25, these slits being aligned with the sides of the crosshead 23 so that the length of the crosshead is virtually increased. The side members 21 and 22 are then bent through an arc of 90° on the lines c—c and d—d, these lines being parallel to the sides of the side members 21 and 22 and extending through the ends of the slits 25, as indicated in Figure 3. The side members 21 and 22 are then disposed in planes perpendicular to the plane of the crosshead 23 and are spaced apart a distance slightly greater than the width of the strip 10. The end portions of the side members 21 and 22 are thereupon bent toward each other through angles of 90° on the lines e—e and f—f, so that the side members 21 and 22 are disposed in rectangular shape, as indicated in Figure 4, and are adapted to embrace the legs 15 and 16 of the member 10. A hole 26 may be provided in the center of the crosshead 23 to receive a rivet 30 projecting from an end face of a screw 31 which is adapted for screw-threaded engagement with the thread in the grooves 12 and 13. The screw 31 is loosely attached to the member 20 by means of the rivet 30 so that it can rotate relatively thereto, and may be provided with the customary slot 32 to receive a screw driver. The screw 31 and the grooves 12 and 13 may be provided with screw threads of ordinary configuration, or, if desired, with buttress threads, the latter having one of its flanks generated by a line segment which remains perpendicular to the axis of the thread as it moves in a helical path, a thread of this description being indicated in Figure 12. This minimizes the spreading effect

which the screw 31 has on the legs 15 and 16 when the screw is set up tightly. When the device is assembled for use, a conductor 40 is first inserted in the member 10 between the legs 15 and 16. The member 20 is then slipped over the member 10 so that the crosshead 23 is slidably disposed between the legs 15 and 16 and the thread of the screw 31 engages the thread in the grooves 12 and 13. The screw 31 is then set up 10 by means of a screw driver until the crosshead 23 is forced tightly against the conductor 40 so as to clamp it against the bottom of the U-shaped member 10, as indicated in Figure 7. The side portions 21 and 22 of the member 20 embrace 15 the legs 15 and 16 so as to prevent these legs from spreading and releasing the screw 31. It is evident that, if desired, two or more conductors may be inserted in the connector as indicated in Figure 9, provided that none of the conductors is 20 of a diameter greater than the space between the legs 15 and 16.

Figures 10 and 11 illustrate the connector used 25 as a terminal for a fuse block 45. As therein shown, the member 10 of the connector is secured to the insulating base of the block by a screw 46 which is in threaded engagement in the hole 11, the latter having been tapped to receive the screw 46. Between the insulating base and the member 10 there is a metal strip 47 which 30 connects the connector to a fuse clip 50 mounted on the base. The connector can also be adapted to any of the uses for which such connectors are employed.

It is evident that various modifications and 35 changes may be made in the embodiments of the invention herein shown and described without departing from the spirit or scope of the invention as defined in the following claims.

What I claim is:—

1. A solderless connector comprising a U-shaped member consisting of a strip of metal bent to shape and adapted to receive an electrical conductor between the legs thereof, a screw between the legs and in threaded engagement therewith, and a skirt member made of flat stock slidably engaging said legs, said skirt member having a central bridging portion extending across the space between said legs at the inner end of said screw and a pair of wing portions each slidably engaging the outer faces of both said legs over a substantial distance in both directions from the plane of said bridging portion. 10

2. In a solderless connector, a clamping member made of a piece of sheet metal cut and bent 15 to shape and comprising a horizontal bridging element and a pair of wing elements at the opposite ends of said bridging element, said wing elements each having a central portion disposed in a plane perpendicular to the plane of the 20 bridging element, each said wing element having end portions bent at right angles to the plane of the central portion and extending both above and below the plane of said bridging element.

3. In a solderless connector, a clamping member comprising a single piece of sheet metal cut and bent to a form having a bridging transverse element and a wing element at each end of said bridging element, each said wing element having a central portion perpendicular to the plane of 30 the bridging element and a pair of end portions perpendicular to the planes of said bridging member and said central portion, said end portions projecting both above and below the plane of said bridging member, and a screw extending 35 up centrally from said bridging element and loosely pivoted thereto for rotation about its own axis.

ERNEST G. JOHANSSON.
